UNITED STATES PATENT OFFICE.

PETER ALFRED JOHNSON, OF GOLDCREEK, MONTANA.

ROTARY ENGINE.

No. 903,864.

Specification of Letters Patent.

Patented Nov. 17, 1908.

Application filed April 20, 1908. Serial No. 428,247.

To all whom it may concern:

Be it known that I, PETER ALFRED JOHNSON, a subject of the King of Sweden, residing at Goldcreek, in the county of Powell and State of Montana, have invented certain new and useful Improvements in Rotary Engines, of which the following is a specification.

This invention embodies novel improvements in rotary engines of the explosive type, and involves certain details of construction which will appear more fully hereinafter.

An essential feature of the invention resides in the provision of a mechanism which may readily be converted into an engine operated by steam or a similar motive fluid.

For a full understanding of the invention and the merits thereof reference is to be had to the following detail description, and to the drawings, in which:

Figure 1 is a side elevation of an engine embodying the invention; Fig. 2 is a vertical longitudinal section; Fig. 3 is a horizontal sectional view; Fig. 4 is a perspective view of the piston; Fig. 5 is a fragmentary sectional view bringing out more clearly the mounting of the parts of the abutment; Fig. 6 is a detail view of one of the parts or sections of the abutment; and Fig. 7 is a detail view showing clearly the relative arrangement of the exhaust valve and exhaust pipes.

Corresponding and like parts are referred to throughout the description and drawings by the same reference characters.

Specifically describing the invention the numeral 1 designates the engine cylinder in which operates the piston 2. The body of the piston 2 is preferably solid and is snugly received in the space between the central portions of the sides of the cylinder, radial wings or blades 3 being carried by the piston 2 and operating in the space 4 provided between the outermost portions of the body of the cylinder 1. The piston 2 is mounted on the shaft 5 and a pulley 6 is preferably carried by the shaft to be connected with suitable power transmitting devices. The cylinder 1 may be of sectional construction, as shown, with its sides connected by bolts or similar fastenings, and the main body portion of the cylinder is surrounded by a cooling jacket 7 between which and the adjacent portions of the cylinder a suitable cooling

medium such as water is adapted to flow. The cooling medium enters the space between the jacket 7 and cylinder 1 from an inlet pipe 8 connected with the top of the jacket, passing from such space through an outlet pipe 9 beneath the cylinder. At one side thereof, the cylinder 1 is formed with a laterally projecting portion constituting an ignition chamber 10 between which and the body of the cylinder is arranged a rotatable feed valve 11.

The valve 11 is operable so that the port thereof will direct the motive fluid from the ignition chamber 10 to either side of an abutment 12 extending across the space 4 of the cylinder 1 and comprising oppositely slidable sections or parts 12'. When the motive fluid is caused to pass to one side of the abutment 12 the force thereof will be directed against the adjacent blade or wing 3 and the piston will rotate in one direction. The rotation of the piston 2 may be reversed by adjusting the feed valve so as to feed the motive fluid into the cylinder 1 at the opposite side of the abutment 12 in an obvious manner, and by mechanism to be hereinafter described. The sides of the cylinder 1 are formed with outwardly projecting housings 13, preferably integral therewith, and in which the sections of the abutment 12 are adapted to slide. The sections 12' of the abutment are movable in opposite directions in order that they may be separated sufficiently to permit the blades 3 to pass by the abutment, and said sections 12' are normally held with the adjacent edges thereof in contact by means of springs 14 arranged in the housings 13.

It will be observed that the sections 12' of the abutment 12 are formed with lateral oppositely extending arms 12", arranged in substantially the same plane and movable in guide extensions 13' of the housings 13 formed on the sides of the cylinder 1. Two springs 14 preferably coöperate with each section of the abutment 12, each of said springs engaging one of the arms 12". The arrangement of the springs 14 with respect to the abutment sections is advantageous in absorbing the shock or jar incidental to contact of the members 3' on the blades 3.

From the foregoing it will be understood that the abutment 12 comprises virtually a movable wall resisting the force of the motive fluid in one direction so that it is caused

to act upon the wings or blades 3 and move the latter in an opposite direction, thereby rotating the piston 2.

Leading outwardly from a side of the cylinder 1 are the exhaust pipes 15 which extend from ports 16 to the casing 17 in which the exhaust valve 18 is mounted. The exhaust valve 18 is of a form similar to the valve 11, as shown in Fig. 7, and controls 10 passage of the exhaust from the cylinder 1 to the outlet 19. Extending in opposite directions from the stems of the valves 11 and 18 are the arms 20 and 21, respectively. A reversing lever 22 is connected with the 15 arms 20 and 21 in order to simultaneously operate the feed and exhaust valves of the engine so that when the feed valve is adjusted to feed the motive fluid to the cylinder at one side of the abutment 12, the exhaust valve will be simultaneously adjusted to open the exhaust pipe 15 at the opposite side of the abutment to the outlet 19.

The engine is preferably used as an explosive engine under which conditions fuel 25 is fed to the ignition chamber 10 from a reservoir 23 arranged above the chamber 10. A valve 24 is adapted to be intermittently operated by a lever 25 which is in turn actuated by a cam wheel 26 on the shaft 5. The 30 wheel 26 is provided with suitable cams adapted to engage a lifter-rod 27 mounted on a side of the jacket 7 and connected with said lever at one end of the latter. The lever 25 is pivoted between its ends and the other 35 end thereof engages the stem 28 of the valve 24. A spring 29 normally holds the valve in a position closing the inlet leading from the reservoir 23 to the ignition chamber 10.

Any suitable means may be used to admit 40 air to the explosion chamber 10 for admixture with the hydrocarbon to provide the explosive mixture. In the drawings a common type of air inlet valve 24^a is shown, the latter being spring seated and adapted to 45 open automatically on the suction caused by the piston. It may be noted that the explosion of the explosive mixture takes place after one of the blades of the piston has passed some distance beyond the abutment, 50 this blade tending to create a vacuum in the ignition chamber by such movement and thereby effecting opening of the valve 24^a to draw atmospheric air into said ignition chamber for admixture with the fuel or 55 hydrocarbon.

A feed pipe 30 controlled by a valve 31 is employed to supply the fuel to the reservoir 23. Ignition of the explosive mixture at proper intervals of time in the chamber 10 60 is effected by an ignition-tube 32 attached in any suitable manner to a wall of the ignition chamber so that the explosive mixture received by the latter on coming into contact with the tube will be caused to explode in 65 the well known manner, the force of the ex-

plosion being directed by the feed valve 11 against the blades or wings 3 of the piston 2. The ignition tube 32 is maintained incandescent by means of a heater 33 embodying a suitable burner supplied with a hydrocarbon from a tank or reservoir 34 with which a pump 35 is connected to force the oil to the burner 33 from the tank 34 by air pressure.

Should it be desired that the engine be converted into one operated by steam or a similar motive fluid, the feeding of fuel from the reservoir 23 into the chamber 10 is discontinued and the tube 32 is not heated. The motive fluid is fed into the chamber 10 by connecting a pipe, or the like, leading from the source of supply of said fluid, with an internally threaded coupling extension 36 which projects from a side of the chamber 10 and which, when the engine is operated by an explosive medium, is closed by a plug 37.

It will be understood that when the engine is used either as an explosive engine, or operated by a motive fluid by connections with the member 36, the sections 12' of the abutment 12 are operated automatically by the blades or wings 3. Each blade or wing 3 of the piston 2 is provided with oppositely extending projections 3' the outer extremities of which are pointed, these projections being adapted to engage the abutment sections 12' at the meeting edges of the latter in order to force the sections apart and permit the wings or blades 3 to pass the abutment in the revolution of the piston. It is preferred that the sections 12' be formed with inclined notches 12'' at the meeting edges so as to facilitate the engagement of the points of the projections 3' on the wings 3 with said sections in effecting separation of the latter for the purpose described. Opposite edges of each projection 3' form inclined guides adapted to ride in contact with the adjacent edges of the abutment sections 12' in separating the latter. Suitable packing for the various parts 1 will be employed on the practical embodiment of the invention, and any desired means is used in order to discontinue the intermittent operation of the valve 24 when the engine is not to be operated by an explosive 1 medium. For the purpose of preventing the lever 25 from actuating the valve 24 when the engine is operated by a motive fluid introduced at 36 into chamber 10, the lifter-rod 27 is made extensible so that the lower section 27' thereof may be adjusted by a set screw to occupy a position wherein it will not be in the path of movement of the cams on the wheel 26.

Having thus described the invention, what 12 is claimed as new, is:

1. In a rotary engine, the combination of a cylinder, a rotary piston therein, an ignition chamber communicating with the cylinder, fuel feeding mechanism and air supply 13

means for said ignition chamber, means for exploding an explosive charge in the said chamber, mechanism for actuating the fuel feeding means and comprising a cam wheel 5 having cams, a lifter rod operable by the cams of the said wheel, means connecting the lifter rod and fuel feeding means, said lifter rod comprising extensible parts, whereby the rod may be thrown into and out of coöperation with the cam wheel to correspondingly 10 continue or discontinue actuation of the fuel feeding mechanism.

2. In a rotary engine, the combination of a cylinder, a rotary piston therein, an ignition chamber communicating with the cylinder, fuel feeding mechanism and air supply 15 means for said ignition chamber, means for exploding an explosive charge in the said chamber, mechanism for actuating the fuel

feeding means and comprising a cam wheel, 20 a lever pivoted to the cylinder and directly coöoperating with the fuel feeding mechanism, and a lifter rod connected with the said lever and engageable by the cam wheel aforesaid, said lifter rod comprising extensible 25 sections, and a set screw for holding the sections of the rod in positions in which the latter is engaged or not engaged during the revolution of the cam wheel, whereby to continue or discontinue the operation of the fuel 30 feeding mechanism.

In testimony whereof I affix my signature in presence of two witnesses.

PETER ALFRED JOHNSON.
